UNITED STATES PATENT OFFICE.

NATHANIEL T. COFFEY, OF NIAGARA FALLS, NEW YORK.

IRONING-BOARD.

1,039,649.

Specification of Letters Patent. Patented Sept. 24, 1912.

Application filed September 20, 1911. Serial No. 650,349.

To all whom it may concern:

Be it known that I, NATHANIEL T. COFFEY, a citizen of the United States, residing at Niagara Falls, in the county of Niagara and State of New York, have invented new and useful Improvements in Ironing-Boards, of which the following is a specification.

The general object of the invention is to support an ironing board by a tripod, the legs of which are adapted to be folded on the board when the same is not in use and to automatically interlock when moved outwardly from the board.

Other objects will appear and be better understood from the following description taken in connection with the accompanying drawings, in which,

Figure 1 is a perspective of the device. Fig. 2 is a bottom plan view with the parts folded.

5 indicates the board which may be of any desired material and contour and 6 a supplemental board which is of reduced size and when in operative position is supported 25 in spaced relation to the upper face of the board 5 by means of a cleat 7 secured to the lower face thereof.

8 indicates a two-jointed strap for connecting the supplemental board to the board 30 5, whereby, the said supplemental board may be adjusted over the upper face of the board 5 as previously described or, when not in use may be folded over the opposite face of the board 5 and secured by a latch 35 9 pivoted to the board 5 all of which is clearly shown in Figs. 1 and 2.

a indicates the tripod support and 11 and 40 12 two legs of this support which are arranged in spaced relation and connected at one end by hinges 13 to the central portion of the board 5; the hinged connection between the board and legs being such as to permit the legs 11 and 12 to swing longitudinally of the board.

45 14 indicates the third leg of the support a. This leg extends longitudinally of the board and through the space between the legs 11 and 12.

50 15 indicates a hinge which connects one end of the third leg 14 to one end portion of the board 5.

16 indicates a cross pin carried by the leg 14 and 17, 18 indicate pins extending from one face of the legs 11 and 12 and forming

abutments for the end portions of the cross pin when the device is in set-up position as shown in Fig. 1.

18 indicates a strap which connects the free end portions of the legs 11 and 12 and forms a carrier for the third leg 14 when 60 folding the said legs from the position shown in Fig. 1 to that shown in Fig. 2, where it will be seen that the strap also provides a keeper for the leg 14. The said strap 18 also prevents displacement of the 65 third leg, when the legs 11 and 12 are swung outwardly from the position shown in Fig. 2 and toward the opposite end of the board, and thereby holds the said leg 14 in such position as to permit of its being moved 70 until the cross pin 16 abuts the pins 17.

In order to prevent the device from toppling while in use, I preferably form the legs 11 and 12 with offset portions 19.

Although I have shown and described one 75 embodiment of my invention it is to be understood that I am not to be limited to the specific construction and arrangement of parts since various changes may be made, within the scope of the appended claims 80 without departing from the spirit or sacrificing any of the advantages of the invention.

What I claim as new is:

A foldable tripod support for ironing 85 boards, having two legs spaced apart and hinged at one end to the central portion of the board so as to swing longitudinally thereof, and a third leg extending longitudinally of the board and through the space 90 between the first-named legs and hinged at one end to one end portion of the board, a cross pin carried by the said third leg and pins projecting from the first-named legs 95 and arranged so as to form abutments for the end portions of the cross pin, when all of said legs are swung outwardly from the board, and an element connecting the first-named legs and forming a support for the free end portion of the third leg during the 100 outward movement of the latter and when all of said legs are folded onto the board.

In testimony whereof I affix my signature in presence of two witnesses.

NATHANIEL T. COFFEY.
